(57) **CLAIM**

The ornamental design for a strainer for beverage shaker, as shown and described.

DESCRIPTION

FIG. 1 is a top, front perspective view of a strainer for beverage shaker showing our new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a back elevation view thereof; and,

FIG. 7 is a bottom plan view thereof.

The strainer for beverage shaker is used within a beverage shaker to strain the contents poured from the beverage shaker.
